CLAIM

The ornamental design for a crib assembly for a patient support, as shown and described.

DESCRIPTION

FIG. 1 is a top view of a crib assembly for a patient support showing our new design.

FIG. 2 is a bottom view of the crib assembly for a patient support of FIG. 1.

FIG. 3 is a right side view of the crib assembly for a patient support of FIG. 1.

FIG. 4 is a left side view of the crib assembly for a patient support of FIG. 1.

FIG. 5 is a top, front, perspective view of the crib assembly for a patient support of FIG. 1; and,

FIG. 6 is a rear view of the crib assembly for a patient support of FIG. 1.

The dashed lines, the areas within them and the unshaded areas bounded between both broken lines and solid lines depict portions of the crib assembly for a patient support that form no part of the claimed design.
